United States Patent Office

Des. 213,303
Patented Feb. 18, 1969

213,303

FACE SHIELD

Paul R. Jones, Long Beach, Calif., assignor to Bates Industries, Inc., Long Beach, Calif., a corporation of California

Filed May 15, 1967, Ser. No. 7,125

Term of patent 14 years

U.S. Cl. D2—233

Int. Cl. D2—03

FIG.1

FIG.2

FIG.3

FIG.4

FIG.5

FIG. 1 is a perspective view of a face shield, showing my new design;

FIG. 2 is a side elevational view thereof;

FIG. 3 is a front elevational view thereof;

FIG. 4 is a top plan view thereof; and

FIG. 5 is a bottom plan view thereof.

I claim:

The ornamental design for a face shield, substantially as shown and described.
